UNITED STATES PATENT OFFICE.

ROBERT L. COCHRANE, OF CHICAGO, ILLINOIS.

RAIL ANCHOR.

Application filed August 9, 1926. Serial No. 128,087.

My invention relates to rail anchoring devices for resisting the longitudinal creeping movement of railroad rails.

The primary object of the invention is to provide an improved one-piece anchor device which may be driven into gripping engagement with one flange of the rail base and which will be maintained in its operative position on said base flange by the gripping action produced. In this connection, I contemplate as one preferred embodiment, an anchor device which may be made from a relatively small metal plate, but which, nevertheless, will provide a relatively wide tie abutting portion and which will also provide rail gripping portions of sufficient strength to resist the stresses and pressure to which devices of this character are subjected when in service.

A more specific object of the invention is to provide an improved rail anchor device which, when in its applied position on a rail, will engage one flange only of the rail base, and to provide in an anchor of this character rail gripping jaw portions having sufficient resiliency to compensate for the expansion and contraction of the rail, and which jaws will also permit the anchor to be applied to rails, the base flanges of which may vary in thickness or contour.

Another object is to provide an anchor of the above character which will take a biting grip on the top and bottom surfaces of a rail in a manner to resist movement of the anchor in a direction to lose its grip on the rail. The portions for engaging the rail base in certain of the embodiments are preferably in the form of teeth arranged in staggered relation to each other and project outwardly from the body in a direction longitudinally of the rail so as to provide an effective increase in the gripping surface of the jaw portions relative to the thickness of the anchor and so that the upper and lower teeth will cooperate with each other to effect a firm shackle hold on the rail when the rail tends to creep longitudinally of the track.

With the above mentioned and other objects in view, the invention consists in the

new and improved constructions hereinafter described and included in the scope of the appended claims.

In the drawings:

Fig. 1 is a plan view of the base portion of a railroad rail showing a rail anchor constructed in accordance with my invention applied thereto.

Fig. 2 is a side view of the anchor shown in Fig. 1, the rail base in this view being shown in section.

Fig. 3 is a cross section taken through the anchor on line 3—3 of Fig. 2.

Fig. 4 is a view in perspective of the anchor device shown in the preceding figures.

Figs. 5, 6 and 7 are views similar to Figs. 1, 2 and 3, showing a slightly modified form of anchor device.

Figs. 8, 9 and 10 are plan, side and perspective views respectively, of another modified embodiment of my invention.

Fig. 11 is a fragmentary plan view of the rail base flange illustrating the manner in which the rail gripping portions of the anchor score the upper and lower surfaces of the rail base.

Fig. 12 is a plan view of a railroad rail showing another embodiment of the invention applied to its operative position on a rail base.

Fig. 13 is a view in perspective of the modification shown in Fig. 12.

Fig. 14 is a sectional view taken on line 14—14 of Fig. 12.

Fig. 15 is a plan view of the blank from which the embodiment shown in Figs. 12 to 14 inclusive, is formed; and

Fig. 16 is a modification of the embodiment shown in Figs. 12 to 15 inclusive.

In Figs. 1 to 4, inclusive, I have shown one embodiment of my invention applied to a railroad rail. This embodiment is made from a flat plate of preferably spring metal. It is formed with a recess 11 adapted to receive one flange of the rail base and is positioned on the rail so that the lower portion 12 of the plate will bear against the vertical face of a cross tie 13 or other stationary part of the roadbed. The recess 11

defines upper and lower jaws 14 and 15 which, when the anchor is in its applied position, are driven into gripping engagement with the top and bottom surfaces, respectively, of the said base flange 16. The upper jaw is formed with slits 17 and 18 which divide the jaw into a vertically disposed gripping portion 19 and into rail gripping teeth 20 and 21. The teeth are bent outwardly in opposite directions from the side planes of the body of the anchor so as to project from the body in a direction longitudinally of the rail.

The lower jaw 15 is slit as indicated at 22 and 23 so as to provide the jaw with a vertically disposed rail engaging portion 24 and with teeth 25 and 26 which are bent outwardly from the side planes of the anchor in substantially the same manner as the teeth 20 of the upper jaw. The said teeth of the upper and lower jaws are so bent, however, that the teeth 20 and 26 project outwardly from one side of the anchor and so that the teeth 21 and 25 project outwardly from the other side.

With the above arrangement of teeth, the pressure on the rail base is substantially equal on both sides of the anchor and the anchor, therefore, is maintained normally in a position substantially perpendicular to the rail base. The angular positions of the teeth are preferably such that their sharp edges 27, 28, 29 and 30 engage the rail base at points outside the side planes of the anchor body so as to increase the effective width of the jaws relative to the thickness of the anchor body. Such arrangement also permits the teeth to flex outwardly with respect to the body so as to compensate for variation in the contour or thickness of the rail base. The sharp rail engaging edges of the teeth are also, preferably, disposed at an angle to the planes of the surfaces engaged so as to confine their engagement largely to the sharp corner edges 27', 28', 29' and 30'. With this arrangement, the sharp corner portions of the teeth bite into the top and bottom surfaces of the rail, when the anchor is driven to its applied position.

The grooves formed by the biting edges of the teeth are disposed preferably at points removed from the edge of the rail base. Under this condition, the said grooves provide shoulders which are engaged by the sharp biting corners of the teeth and thereby lock the anchor against backing off the rail. The resiliency of the teeth exerts spring pressure against the rail base, so as to hold the teeth in interlocked engagement with the walls of the several grooves.

In operation, the anchor device is inserted over one flange of a rail base in a position to bear against one of the vertical faces of the cross tie. The anchor may be then driven transversely of the rail until the ver-

tical edge of the rail base engages or substantially engages the vertical portion of the recess 11. In this position of the anchor the portions 19 and 24 grip the top and bottom surfaces of the rail base with a wedging engagement and the teeth 20, 21, 25 and 26 take a biting engagement, as previously described, upon the top and bottom surfaces of the rail base. The distance which the device is driven upon the base flange will determine largely as to whether or not both of the portions 19 and 24 are in engagement with the rail base. In some installations the said portions 19 and 24 may be out of engagement due to the fact that the thickness of the rail base is such that the tooth portions are not required to flex to such position as will permit the said portions 19 and 24 to be driven into engagement with the rail base. In most installations, however, the anchor will engage at the points 19 and 24. When the anchor is applied in the above manner any tendency of the rail to creep in the direction indicated by the arrow in Fig. 1, will exert a pressure against the lower portion of the anchor device so as to tend to rock the anchor about a horizontal axis so that the teeth 21 and 26 are forced into an increased gripping engagement with the rail base, that is to say, such creeping pressure has a tendency to effect a shackle grip, through the teeth 21 and 26 upon the top and bottom surfaces of the rail base. There is, ordinarily, no rocking movement, only a tendency to rock.

In the event that the anchor is applied so as to bear against the opposite vertical face of the cross tie, the shackle engagement is effected through the teeth 20 and 25. It will be noted also that by reason of the resilient pressure exerted by the teeth against the rail base, any tendency that the anchor may have to back off the rail will tend to force the sharp pointed edges of the teeth deeper into the surfaces of the rail base.

In Figs. 5 to 7 inclusive, I have shown an anchor device of the general character shown in the preceding figures, but which is modified in some respects. In this modification the end tooth 26' of the lower jaw portion of the anchor, instead of being bent at an angle as shown in Figs. 1 to 4 inclusive, is disposed substantially in the vertical plane of the body. The arrangement of the said tooth insures a firm bearing of the entire anchor face 31 against the cross tie 32, the edge 33 of the tooth is so sheared that it is normally at an angle to the bottom face of the rail base so that the outer end of the tooth will bite into the rail substantially as shown in Fig. 6.

The slits 34, 35, 36 and 37 are, preferably, of sufficient width so that they may be formed by punching, or if desired, by a shearing process. The ends may be formed

with sharp or rounded corners or with other suitable configurations that will facilitate the forming of the slit.

In other respects the form of the invention shown in Figs. 5, 6 and 7 may be, and preferably is the same as that previously described in connection with Figs. 1 to 4 inclusive.

In Figs. 8, 9 and 10, I have shown another modification. In this modification the teeth 38, 39, 40 and 41 extend transversely of the rail at an angle to the center of the anchor so as to diverge from each other. In other respects the anchor may be the same as that shown in Figs. 1 to 4 inclusive.

With the teeth disposed at the diverging angle shown, the grooves formed in the rail base have a corresponding divergence with respect to the vertical plane of the anchor. Therefore, any outward movement of the anchor at right angles to the rail, that is to say, any movement in the direction to loosen the grip of the anchor on the rail is resisted by the side walls of the diverging grooves formed in the top and bottom surfaces of the rail base. It will also be seen from an inspection of the drawings that the diverging angular portions of the teeth present a relatively wide cutting edge in opposition to the forces tending to move the anchor in the direction to loosen its grip on the rail. The arrow shown in Fig. 11 illustrates the direction in which the anchor is moved in removing it from the rail, which path of movement intersects the angle of the grooves in the top and bottom surfaces of the rail base.

In Figs. 12 to 15 inclusive is shown another modification in which jaw portions 42 and 43 are disposed in spaced relation to each other longitudinally of the rail. This embodiment is made preferably from a flat metal blank of the configuration shown in Fig. 15. The blank is bent along the dotted vertical line 44 to the U-shaped configuration shown in Fig. 13. The blank is provided with rail base receiving recesses 45 and 46 which, when the blank is bent to the position shown in Fig. 13, are adapted to fit over the rail base. The said recesses are preferably formed out of alignment as indicated in Fig. 15, so that the anchor is subjected to torsional stress when the jaw portions are driven into gripping engagement with the rail base. In Fig. 16 I have shown an anchor device somewhat similar to the form of the invention illustrated in Figs. 14 and 15, except that the spaced jaw members 42^a, 43^a are provided with angularly disposed rail engaging teeth substantially of the form shown in Figs. 1 to 4 inclusive. The rail engaging edges of the teeth extend at an angle to the planes of the surfaces engaged so as to be forced by their resiliency into biting engagement with the rail

base. The rail engaging recesses are preferably formed out of alignment with each other and the anchor, in addition to the resiliency of the teeth is subjected to torsional stress when the device is applied. If desired, however, the jaws may be formed in alignment, so as to be applied without the torsional stress above referred to. In such constructions the spring pressure of the teeth will be sufficient to hold the teeth in their interlocking engagement with the grooves formed in the rail by the biting action of the teeth.

While I have shown and described my invention in connection with several specific embodiments, it will be understood that I do not wish to limit myself to the specific embodiments shown, except insofar as the appended claims may be limited.

I claim:

1. A rail anchor for engagement with one flange only of a rail base, comprising a member formed with rail engaging portions spaced with relation to each other longitudinally of the rail and adapted to be driven transversely of the rail into biting engagement with the rail base.

2. A rail anchor for engagement with one flange only of a rail base, comprising a member formed with rail engaging portions normally spaced out of alignment with each other when the anchor is free of the rail and adapted to be driven transversely of the rail into biting engagement with the rail base.

3. A one-piece rail anchor adapted to engage one flange only of a rail consisting of a member formed with jaw portions normally spaced with relation to each other longitudinally of the rail base and adapted to exert a resilient gripping action on the surfaces of said rail base.

4. A one-piece spring metal rail anchor adapted to engage one flange only of a rail base, consisting of a member formed with jaw portions normally spaced with relation to each other longitudinally of the rail and adapted to exert a resilient gripping action on the surfaces of said base flange.

5. A one-piece spring metal rail anchor adapted to engage one flange only of a rail base, consisting of a member formed with jaw portions normally spaced with relation to each other longitudinally of the rail and adapted to be flexed vertically during the application of the device to a rail to exert a resilient gripping action on the surfaces of said base flange.

6. A rail anchor for engagement with one flange only of a rail base comprising a body portion formed with rail base engaging jaws for gripping the top and bottom surfaces of a rail base, one of said jaws being formed with a portion which projects outwardly from the body of the anchor in a

- 4
- direction longitudinally of the rail and provided with a sharp edge adapted to embed itself in the rail during the application of the anchor to its operative position.
5. 7. A rail anchor for engagement with one flange only of a rail base comprising a body portion formed with rail base engaging jaws for gripping the top and bottom surfaces of a rail base, one of said jaws being formed with a portion which projects outwardly from the body of the anchor in a direction longitudinally of the rail and adapted to be stressed and embedded in the rail base during the application of the anchor to the rail.
10. 8. A rail anchor for engagement with one flange only of a rail base and adapted to be driven transversely of the rail to its applied position, comprising a body portion formed with rail base engaging jaws for engaging the top and bottom surfaces of a rail base, one of said jaws being formed with a portion which projects outwardly from the body of the anchor in a direction longitudinally of the rail and adapted to be stressed and embedded in the rail base during the application of the anchor to its applied position.
15. 9. A rail anchor for engagement with one flange only of a rail base and adapted to be driven transversely of a rail to its applied position, comprising a body portion formed with rail base engaging jaws for engaging the top and bottom surfaces of a rail base, one of said jaws being formed with portions being bent outwardly from the sides of the body in opposite directions longitudinally of the rail and adapted to be stressed and embedded in the rail base during the application of the anchor to the rail.
20. 10. A rail anchor for engagement with one flange only of a rail base and adapted to be driven transversely of the rail to its applied position, comprising a body portion formed with rail base engaging jaws for gripping the top and bottom surfaces of the rail base, said jaws being formed with portions bent outwardly from the sides of the body in opposite directions longitudinally of the rail and adapted to be stressed and embedded in the rail base during the application of the anchor to the rail.
25. 11. A rail anchor adapted to engage with one flange only of a rail, comprising a body formed with rail base engaging jaws adapted to be driven transversely of the rail in biting engagement with the top and bottom surfaces of the rail base; said jaws being formed with gripping elements which are bent outwardly from opposite sides of the body.
30. 12. A rail anchor adapted to engage with one flange only of a rail, comprising a body formed with rail base engaging jaws adapted to be driven transversely of the rail into biting engagement with the top and bottom surfaces of the rail base; said jaws being formed with gripping elements which are bent outwardly from the opposite sides of the body and are confined in their engagement with the rail to points remote from the longitudinal edge of the rail base.
35. 13. A rail anchor adapted to engage with one flange only of a rail, comprising a body formed with rail base engaging jaws adapted to be driven transversely of the rail into biting engagement with the top and bottom surfaces of the rail base; said jaws being formed with yieldable gripping elements which are bent outwardly from the opposite sides of the body and are confined in their engagement with the rail to points remote from the longitudinal edge of the rail base.
40. 14. A rail anchor adapted to engage with one flange only of a rail, comprising a body formed with rail base engaging jaws adapted to be driven transversely of the rail into biting engagement with the top and bottom surfaces of the rail base; said jaws being formed with yieldable gripping elements arranged in staggered relation to each other and confined in their engagement with the rail to points removed from the longitudinal edge of the rail base.
45. 15. A rail anchor comprising a body portion formed with jaws and adapted to be driven transversely of the rail into gripping engagement with the rail base; the said jaws being formed with teeth arranged in staggered relation to each other and adapted to bite into the rail base during the application of the anchor to the rail.
50. 16. A rail anchor comprising a body portion formed with jaws and adapted to be driven transversely of the rail base into gripping engagement with the rail base; the said jaws being formed with teeth arranged in staggered relation to each other and each provided with a sharp biting edge disposed at an angle to the plane of the surface of the rail base engaged and adapted to bite into the rail base during the application of the anchor to the rail.
55. 17. A rail anchor comprising a body portion formed with jaws and adapted to be driven transversely of the rail into gripping engagement with the rail base; the said jaws being formed with teeth arranged in staggered relation to each other, and each tooth being bent outwardly from the body to present a corner edge in a position to engage the rail base, whereby said corner is forced into biting engagement with the surface engaged thereby during the application of the device to a rail.
60. 18. A rail anchor comprising a body portion formed with jaws and adapted to be driven transversely of the rail into gripping engagement with the rail base; said jaws being formed with rail gripping portions dis-

- posed in line with the body of the device and with teeth arranged in staggered relation to each other adapted to bite into the rail base during the application of the anchor to the rail.
19. A rail anchor comprising a body portion formed with jaws and adapted to be driven transversely of the rail into gripping engagement with the rail base; said jaws being formed with rail gripping portions disposed in line with the body of the anchor and with teeth arranged in staggered relation to each other and provided with sharp biting edges disposed at an angle to the plane of the surface of the rail base engaged and adapted to bite into the rail base during the application of the anchor to the rail.
20. A rail anchor adapted to grip one flange only of a rail base comprising a body portion formed with jaws adapted to be driven transversely of the rail into gripping engagement with said rail base; the said jaws being formed with teeth arranged in staggered relation to each other and adapted to bite into said rail base during the application of the anchor to the rail.
21. A rail anchor adapted to engage one base flange only of a rail and comprising a body portion formed with jaws adapted to be driven transversely of the rail into gripping engagement with said base flange; the said jaws being formed with teeth arranged in staggered relation to each other and each provided with a sharp biting edge disposed at an angle to the plane of the surface of the rail base engaged and adapted to bite into the rail base during the application of the anchor thereto.
22. A rail anchor adapted to engage one base flange only of a rail base, comprising a body portion formed with jaws and adapted to be driven transversely of the rail into gripping engagement with the rail base; the said jaws being formed with rail gripping portions disposed in line with the body of the device and with teeth arranged in staggered relation to each other adapted to bite into the rail base during the application of the anchor to the rail.
23. A one-piece rail anchor comprising jaws formed with teeth disposed at an angle to each other and adapted to be driven into biting engagement with the top and bottom surfaces of the rail base.
24. A one-piece rail anchor comprising jaws formed with teeth disposed at an angle to each other and adapted to be driven into biting engagement with the top and bottom surfaces of the rail base, the said teeth being so positioned that any tendency to rock the anchor about an axis transversely of the rail base tends to effect a shackle grip of the anchor on the top and bottom surfaces of the rail base.
25. A one-piece rail anchor adapted to be driven into gripping engagement with one flange only of a rail and comprising jaws formed with teeth disposed at an angle to each other and adapted to be driven into biting engagement with the top and bottom surfaces of the said base flange, the biting edges of said teeth being disposed at an angle to the planes of the surfaces engaged, whereby said biting engagement is confined to the outer edges of the teeth.
26. A one-piece rail anchor comprising jaws formed with teeth disposed at an angle to each other and adapted to be driven into biting engagement with the top and bottom surfaces of the rail base and adapted to groove the rail during the application of the anchor and to interlock with the walls of said groove.
27. A one-piece rail anchor comprising jaws adapted to be driven into gripping engagement with one flange only of a rail base and formed with teeth which bite into the top and bottom surfaces of the rail base to provide grooves, the said teeth being resilient, whereby they are held in interlocking engagement with the walls of said grooves.
28. A one-piece rail anchor comprising jaws adapted to be driven into gripping engagement with one flange only of a rail base and formed with teeth which bite into the top and bottom surfaces of the rail base to provide grooves which diverge from each other transversely of the rail.
29. A one-piece rail anchor comprising jaws adapted to be driven into gripping engagement with one flange only of a rail base and provided with teeth bent outwardly from opposite sides of the body and disposed at diverging angles with relation to each other so as to form in the top and bottom surfaces of the rail base grooves disposed at an angle to the line over which the anchor is moved to remove it from the rail.
30. A one-piece rail anchor comprising jaws adapted to be driven into gripping engagement with one flange only of a rail base and formed with teeth which bite into the base flange of the rail to provide grooves; the said teeth being resilient and the biting edges thereof being disposed at an angle to the planes engaged so as to confine the biting engagement of the teeth to their outer corners.
31. A rail anchor for engaging one flange only of a rail base, made from a flat plate of spring metal bent to a substantially U-shape configuration to provide jaw portions, spaced with relation to each other longitudinally of the rail, said jaw portions being formed with recesses normally out of alignment with each other when the anchor is free of the rail, whereby movement of said jaws to their rail gripping positions subjects the anchor to torsional stress.

32. A rail anchor for engaging one flange only of a rail base, made from a flat plate of spring metal bent to a substantially U-shape to provide jaw portions spaced with relation to each other longitudinally of the rail, said jaw portions being formed with recesses normally out of alignment with each other when the anchor is free of the rail, whereby movement of said jaws to their rail gripping positions, subjects the anchor to torsional stress, and said jaws being formed with a plurality of resilient teeth arranged in staggered relation to each other and adapted to bite into the top and bottom surfaces of the rail base when the anchor is applied to the rail.

ROBERT L. COCHRANE.
